SHOE LAST

Peter P. Waraxa, Milwaukee, Wis., assignor to
 Nunn, Bush & Weldon Shoe Company, Milwaukee, Wis.

Application January 21, 1932. Serial No. 587,949

5 Claims. (Cl. 12—141)

This invention appertains to shoe lasts and more particularly to novel means for connecting the insole of a shoe to the last.

In this art, it is the common and universal practice to temporarily tack the insole to the last during the various shoe making operations. This practice has many inherent disadvantages long recognized by shoe manufacturers. Some of these disadvantages are, the cost of the tacks, the tacking machines and the operation of tacking; the cost of the tack pulling machines and the operation of pulling the tacks; the damage often caused to the insoles by the tack pulling machine; the necessity of filling up the tack holes and the pounding down of the rough edges made by the tacks; the inspection of the shoes for insole tacks and the danger of injury to the inspector's hand if a tack is encountered, and the hazard of leaving an insole tack in the shoe and the consequent likelihood of injury to the wearer.

It is, therefore, a primary object of my invention to provide a novel means for detachably connecting the insole to the last, whereby the use of tacks and the consequent disadvantages, as outlined above, are entirely eliminated.

Another prime object of my invention is the provision of novel means for connecting an insole to a last embodying latches connected with the last for engagement with the insole, the latches acting to firmly hold the insole in proper position on the last and being of such a construction as to permit the quick and easy placing of the same into and out of operative position relative to the last and insole.

A further salient object of my invention is the provision of novel means for forming the latches to permit the effective detachable engagement thereof with the last and the effective engagement thereof with the insole, so that the insole will be engaged both at its marginal edge and at the inseaming lip, whereby the insole will be properly held for obtaining the most advantages during the various shoe operations.

A still further object of my invention is to provide an improved device of the above character, which will be durable and efficient in use, one that will be very simple and easy to manufacture, and one in which the latches and last can be repeatedly used.

With these and other objects in view, the invention consists in the novel construction, arrangement and formation of parts, as will be herein-after more specifically described, claimed and illustrated in the accompanying drawing in which:

Figure 1 is a bottom plan view of a last con-

structed in accordance with my invention and showing an insole held thereon by my novel latches, one of said latches being shown partly in section;

Figure 2 is a fragmentary detail section taken on the line 2—2 of Figure 1, looking in the direction of the arrows, illustrating the construction of one of the novel latches and the keeper carried by the last;

Figure 3 is a fragmentary side elevation of my improved last, showing an insole connected therewith.

Referring to the drawing in detail, wherein similar reference characters designate corresponding parts throughout the several views, the letter "A" generally indicates my improved last and "B" the novel latches employed for detachably holding the insole "C" in proper position on the last "A".

The last "A" is of any preferred shape and is constructed in accordance with the general approved type of devices of this character, with the exception, that in accordance with my invention I employ at spaced points novel keepers for engagement by the latches "B".

As shown, I provide a pair of these keepers adjacent to the front of the last and a pair of these keepers adjacent to the rear end of the sole portion of the last, but it is to be understood that more or less of these keepers can be employed. Each keeper embodies a keeper plate 5, preferably formed of metal and counter-sunk flush with the face of the last. As illustrated, each keeper plate is held in place by the use of suitable screws 6, but it is obvious, that other means can be employed for holding the keeper plates in position. The keeper plates, each embody a sole portion 7 and a substantially right angular disposed side last portion 8, which is provided with a keeper notch 9. The last at this point can likewise be notched as at 10, so as to insure the proper engagement of each latch "B" with its respective keeper.

The insole "C" which is placed on the face of the last "A" is of conventional character and will not be described in detail, but it is to be noted that the same embodies the upstanding insoling lip 11 and marginal flange 12.

The latches "B" are of novel construction and form one of the salient features of my invention and each of the latches embody a hook 15 for engaging over its keeper plate and the outer ends of the hooks, remote from the bills thereof, are provided with yokes 16 for receiving the latch levers 17. Suitable pivot pins 18 are employed for connecting the latch levers with the yoke portions 16

of the hooks 15, whereby said levers can be swung relative to the hooks. The outer ends of the latch levers are of a substantially cam-shaped form, as indicated by the reference character 19, and these 5 cam portions 19 swing in between the arms of the yoke portions 16 of the hooks for engaging the marginal flange 12 of the insole "C", as will be later described. Each latch lever 17 is provided with an inwardly directed manipulating handle portion 20, the inner end of which carry an abutment shoulder or lug 21 for engaging the inner face of the lip 11 of the insole "C". These shoulders or lugs 21 are arranged in spaced relation to the cams 19 and depend from the latch levers so 10 as to engage over the lip 11 and can be seen by referring to Figure 2 of the drawing.

In use of my improved device, the insole is placed on the face of the last "A" after which the hooks 15 of the latches are placed in engagement 20 with the keeper plates 5 and the latch lever handles 20 are engaged by the hands of the operator and are swung downward over the face of the insole, so that the cam portions 19 thereof will ride on and grip the marginal edge 12 of the insole 25 and firmly hold the insole to the last, and the latches in position. The downward swinging movement of the latch lever handles 20 will swing the shoulders or lugs 21 in engagement with the lip 11 and consequently, the insole will be grasped both at its marginal edge 30 and at its lip. Engagement of the shoulders or lugs 21 not only act as means for firmly holding the insole in place, but also as means for slightly stretching the insole across the last and consequently holding the insole in proper place on the 35 last.

The usual shoe making operations can now be proceeded with and the latches can be readily removed both from the insole and last at the proper 40 time.

From the foregoing description, it can be seen that I have provided means whereby an insole can

be quickly and easily attached to a last without the use of tacks, thereby eliminating all of the disadvantages heretofore inherent with the use of tacks for this purpose.

Changes in detail may be made without departing from the spirit or the scope of this invention, but what I claim as new is:

1. The combination with a last having keeper plates secured thereto at spaced points, of insole gripping clamps having means for detachably engaging said keeper plates. 80 85

2. The combination with a last having a plurality of spaced marginal keeper plates, of means for detachably connecting an insole to the last including a plurality of latches, each of said latches including a hook for detachably engaging its respective keeper plate and a cam lever pivotally carried by the hook, the cam lever being mounted for swinging binding engagement with the marginal edge of the insole. 90 95

3. The combination with a last having a plurality of spaced marginal keeper plates, of means for detachably connecting an insole to the last including a plurality of latches, each of said latches including a hook for detachably engaging its respective keeper plate and a cam lever pivotally carried by the hook, the cam lever being mounted for swinging binding engagement with the marginal edge of the insole, and an insole lip engaging shoulder carried by each latch lever. 100 105

4. In a device of the above character for holding an insole on a last, a hook, a cam lever pivotally carried by the hook, and an insole lip engaging shoulder formed on the cam lever in spaced relation to the cam thereof. 110 115

5. In a device for detachably securing an insole on a last, a hook having a yoked end, a cam lever pivotally carried by the hook arranged between the arms of the yoked end, and an insole lip engaging shoulder on the cam lever in spaced relation to the cam end thereof. 120
